(57) **CLAIM**

The ornamental design for a three-prong golf tee, as shown and described.

DESCRIPTION

FIG. 1 is a perspective view of a three-prong golf tee in a first embodiment in accordance with my design;

FIG. 2 is a front elevation view thereof;

FIG. 3 is a back elevation view thereof;

FIG. 4 is a right side elevational view thereof;

FIG. 5 is a left side elevational view thereof;

FIG. 6 is a top view thereof;

FIG. 7 is a bottom view thereof;

FIG. 8 is a perspective view of a three-prong golf tee in a second embodiment in accordance with my design;

FIG. 9 is a front elevation view thereof;

FIG. 10 is a back elevation view thereof;

FIG. 11 is a right side elevational view thereof;

FIG. 12 is a left side elevational view thereof;

FIG. 13 is a top view thereof; and,

FIG. 14 is a bottom view thereof.

The dashed lines shown in the figures depict portions of the article that form no part of the claimed design.

1 Claim, 12 Drawing Sheets
